UNITED STATES PATENT OFFICE

BENJAMIN BELCHER, OF CHICOPEE FALLS, MASSACHUSETTS, ASSIGNOR
OF ONE-HALF HIS RIGHT TO JOHN W. BELCHER, OF SAME PLACE.

IMPROVEMENT IN STRAW-CUTTERS.

Specification forming part of Letters Patent No. 174,057, dated February 29, 1876; application filed February 2, 1876.

To all whom it may concern:

Be it known that I, BENJAMIN BELCHER, of Chicopee Falls, in the county of Hampden and State of Massachusetts, have invented new and useful improvements in that class of feed-cutters used for cutting hay and straw, which improvements are set forth in this specification in such full, clear, and exact terms as to enable any person skilled in the art to which these appertain to make, construct, and use the same, reference being had to the accompanying drawing.

My invention relates to that class of machines known as "lever-cutters," in which the knife is attached to a lever, and cuts by coming in contact with a stationary metallic bed-plate on the mouth of the box, through which the substance to be cut is supplied, so that as the knife is brought down the cutting is done on the principle of an ordinary pair of shears; and my improvements consist, first, in a device for a ready lateral and angular adjustment of the knife, and a provision for detaching the knife by merely loosening screws, without the necessity of taking them out; and, secondly, in a device for a lateral and angular adjustment of the lever which carries the knife.

I will now proceed to describe the construction and operation of my improved machine, referring to the drawing herein, in which—

Figure 1 is an elevation of a feed-cutter embodying my invention, the dotted lines showing the position of the knife when a cut is fully made, and the lever has completed its descent. Fig. 2 is a plan of that part of a feed-cutter which contains my improvement, with the knife and its carriage detached. Fig. 3 is a sectional side view, showing the relative position of the knife and its mode of operation. Fig. 4 is a sectional view of the pivoted end of the lever, on the line x of Fig. 1, showing the mode of obtaining both a lateral and an angular adjustment of the lever B.

A represents the box containing the substance to be cut, and is supported upon a suitable frame or legs. This box is provided at its mouth with a metallic frame, a , from

which frame projects the stud b , which serves as a fulcrum for the lever B, to which, when in use, the knife is attached. On the lever B are slotted lugs c , to receive the screw-bolts d , which pass through projections e on the knife-carriage f . C represents the knife when attached to its carriage. D represents the pivoted end of the knife-bearing lever, g being a sleeve which is slipped on the stud b , and secured in any convenient manner, and $h\ h\ h$ being set-screws passing through the projecting end of the lever, this device being independent of, although it may be used in connection with, the device set forth in claim 1 hereof.

It may readily be seen, without further explanation, that by means of the screw-bolts d the knife may be securely fixed to the lever, and may easily be detached by merely loosening the said screw-bolts, and sliding them outward through the open ends of the slotted lugs, without the necessity of withdrawing them, and by the same means both lateral and angular adjustments of the knife can be made.

In place of the screw-bolts sliding, as described, through the open end of the slotted lugs, ordinary slots and set-screws, or their mechanical equivalents, may be used.

It must also be obvious to any person skilled in the art to which this invention appertains, that, by means of any three of the set-screws $h\ h\ h$, which operate independently of each other, the knife-bearing lever may be adjusted to the sleeve g , so as to bring the lever as close to the frame as may be desired, and its parallelism with the mouth-piece be regulated so as to secure the greatest efficiency of which the cutting apparatus is capable.

The sleeve g is represented, in this instance, as having a square outer surface; but, without deviating from the principle of this invention, it may also be made round, so as to fit into a corresponding space in the fulcrum end of the lever.

Having thus fully described my invention, what I claim as new, and desire to secure by Letters Patent, is—

1. In a straw-cutter, the knife-carriage *f*, provided with projections *e*, attached to lever *B*, provided with slotted projections *c* by set-screws *d*, in the manner and for the purpose set forth.

2. The combination, in a straw-cutter, of the lever *B*, fulcrum-stud *b*, sleeve *g*, and set-

screws *h*, substantially as and for the purposes herein set forth.

BENJAMIN BELCHER.
